[57] CLAIM

The ornamental design for a universal rotary trailer hitch, as shown and described.

DESCRIPTION

FIG. 1 is a perspective illustration of the universal rotary hitch;

FIG. 2 is a top plan view of the invention as disclosed in FIG. 1;

FIG. 3 is a bottom plan view of the invention as disclosed in FIG. 1;

FIG. 4 is a left side elevation view of the invention as disclosed in FIG. 1;

FIG. 5 is a right side elevation view of the invention as disclosed in FIG. 1;

FIG. 6 is a front elevation view of the invention as disclosed in FIG. 1; and,

FIG. 7 is a rear elevation view of the invention as disclosed in FIG. 1.

The broken line showing of a fragmented structure is for illustrative purposes only and forms no part of the claimed design.
